MACHINE FOR OPERATING UPON HIDES,
SKINS, AND PIECES OF LEATHERHarrie A. Ballard, Beverly, Mass., assignor to The
Turner Tanning Machinery Company, Port-
land, Maine, a corporation of Maine

Application June 19, 1933, Serial No. 676,501

26 Claims. (Cl. 149—16)

This invention relates to machines for operating upon hides, skins, and pieces of leather. While the invention is illustrated as embodied in a machine for fleshing hides and skins it is to be understood that the invention and various important features thereof may have other applications and uses.

Machines for performing such operations as fleshing, unhairing, and putting-out or setting upon hides, skins, and pieces of leather comprise characteristically a bladed cylinder for operating upon the work while the latter is supported by a bed roll, one or more feed rolls being provided for co-operation with the bed roll in feeding pieces of work past the bladed cylinder. It is an object of the invention to make provision for automatic adjustment of the bed roll and cylinder relatively to each other for each piece of work placed upon the bed roll for treatment. In this way each piece of work may receive individual treatment in the sense that the pressure under which the piece of work is treated is suited to that piece of work, particularly with respect to the thickness thereof as gaged at some selected point.

Following the usual beamhouse operations, hides and skins are subjected to tanning operations to convert them into leather. It is not, at the present time, common practice to sort hides, before tanning, into various batches according to thickness although it would be distinctly advantageous to do so since thinner hides are often subjected for a longer time to the action of tanning solutions in the vat than is necessary, treatment of the hides usually continuing until the thickest of the batch are thoroughly tanned throughout. It is considered that a distinct step in advance would be made by providing, in connection with machines of the beamhouse type, facilities for sorting the hides into batches according to thickness dimensions thereof, especially if little or no extra effort be required on the part of the operator. Accordingly, it is a further object of the invention to indicate to the operator the thickness dimensions of the various hides as they are subjected to one or another of the beamhouse operations, so that the hides may be assorted correspondingly into piles as they are delivered from the machine operation.

With the above and various other objects in view there is provided in the illustrated machine, as an important feature of the invention, means controlled by the work for securing relative adjustment between a bladed cylinder and a bed roll as a preliminary to treatment of each piece

of work by the bladed cylinder while the work is backed by the bed roll. In this way, the pressure at which a given operation is performed is suited to each piece of work with correspondingly good results. Conveniently a gaging means for the work is associated with the bed roll to adjust the latter with respect to the bladed cylinder, adjustment of the bed roll being controlled by each piece of work through the operation of said gaging means, and the arrangement being such that a piece of work is introduced into the gaging or caliper means by throwing it over the bed roll in the manner now common in operating all beamhouse machines. As illustrated, the arrangement is such that, as the bed roll moves to open position, gaging members, one of which moves with the bed roll, become relatively spaced to receive a portion of the work as the latter is placed upon the bed roll, the gaging members moving toward each other to gage or caliper the work as the bed roll moves toward the bladed cylinder. Immediately after the gaging operation takes place the bed roll is secured in its adjusted relation to its operating means and, perforce, to the bladed cylinder so that the work is operated upon at a pressure predetermined by the gaging means. Since machines of the beamhouse type commonly operate upon only one-half of a piece of work at each cycle of the machine, the work being reintroduced for treatment of the portion remaining untreated following the first introduction into the machine, provision is made for retaining the adjusted relation of the bed roll during treatment of the second half of the work. In other words, each piece of work is gaged but once and the pressure at which treatment will be performed is fixed but once for each piece of work although it is introduced twice into the machine to complete treatment thereof.

It is an important feature of the invention that means is provided, in association with a bed roll movable between work receiving and work presenting positions with respect to a bladed cylinder in a machine of the beamhouse type, for indicating to the operator the thickness dimension of each piece of work treated by the machine, thus enabling him to place the treated hide with others of like thickness dimension in a selected pile. In this way sorting of the hides for thickness is greatly facilitated and without any extra operation, such as might be prohibitive under certain conditions because of the time or labor involved.

These and other important features of the invention and novel combinations of parts will

now be described in detail in the specification and then pointed out more particularly in the appended claims.

In the drawings,

5 Fig. 1 is a view in front elevation and partly in section of a machine showing one embodiment of the invention;

Fig. 2 is a sectional view along the line II—II of Fig. 1;

10 Fig. 3 is a sectional view along the line III—III of Fig. 1;

Fig. 4 is a detail view of a cam disk shown at the bottom of Fig. 3; and

15 Fig. 5 is a detail view of other parts shown in Fig. 3.

In the illustrated machine, which is especially designed for performing fleshing operations upon hides, there is provided a bladed cylinder 10 mounted for rotation in bearings carried by the 20 frame of the machine, means (not shown) being provided for driving the bladed cylinder continuously at a relatively high rate of speed.

For presenting a piece of work to the bladed cylinder 10 there is provided a bed roll 12 mounted on a shaft 14 carried in bearings at the upper ends of swing arms 16 mounted for effective swinging movement about a shaft 18. Just before the bed roll 12 reaches work presenting position with respect to the bladed cylinder 10 it 30 presses the work against a feed roll 20, shaft 22 of which is carried in the usual manner by blocks (not shown) slidable in the frame of the machine and held yieldingly in position by springs one of which is shown at 24 in Fig. 2. As illustrated, 35 the shaft 22 is provided with a sprocket wheel 26 (Fig. 1) arranged to be driven by a chain connection to a sprocket 28 on a power shaft 30. The feed roll shaft 22 has fixedly secured thereto a gear 32 with which a gear 34 on the shaft 14 comes into mesh when the bed roll 12 moves into 40 co-operative relation with respect to the feed roll 20, the arrangement being such that the bed roll 12 is driven from the feed roll 20 and ceases to be driven as soon as it moves away from the feed 45 roll.

As an important feature of the invention, means is provided for gaging or caliperizing each piece of work and adjusting the spacing of the bed roll with respect to the bladed cylinder in accordance with the results of the caliperizing operation. It is to be understood that the spacing referred to is that found when the bed roll has reached its closed or work presenting position with respect to the cylinder. By this means the pressure of the fleshing operation is adjusted to each piece of work in accordance with the thickness dimension thereof. As shown, the caliperizing or gaging means comprises two gage members 40, 42, of which the gage member 42 may be considered 50 the fixed gage while gage member 40 is the movable gage in the caliperizing operation. The gage member 40 is carried at the corresponding upper ends of bell crank levers 44 pivotally mounted upon the shaft 18, the bell crank levers 44 each having a horizontal arm 46 carrying a weight 48 adjustable thereon, and said arms 46 being arranged to contact with stops 50 mounted on the machine frame when the bed roll is moving toward work receiving position. Extending 55 from the hub portion of the bell crank lever 44, is an extension 52 provided with a set screw 54 the lower end of which is adapted to contact with a short arm 56 carried rigidly by the shaft 18. Extending between and connected to the arm 56 and the arm 46 of each bell crank 44 is a

spring 58 of sufficient strength to hold the screw 54 in contact with the arm 56 during gaging operations, the said springs yielding at other times in the operation of the machine. It will be understood, then, that if the gage member 40 be moved in a counterclockwise direction in Fig. 2, as for instance by the introduction of a piece of work between the members 40 and 42, it will cause rotation of the shaft 18 in a counterclockwise direction, the spring 58 permitting relative movement between the bell crank lever 44 and the shaft 18 under excessive or suddenly applied pressure, or when the shaft 18 is locked as will be hereinafter described.

5 The other gage member 42 is carried by a pair of arms 60 (Figs. 1 and 2) pivoted upon the shaft 18 and pivotally connected at their lower ends by pins 62 to bifurcated members 64 which form part of links or pitmen 66, the other ends of which are pivotally connected to crank arms 68 on the drive shaft 30. As most clearly shown in Fig. 1 the swing arms 16 of the bed roll 12 are pivotally connected at their lower ends by rods 70, 71 to the arms 60 carrying the gage 42. The swing arms 16 are also connected adjacent their upper ends to the arms 60 of the gage member 42 so that the swing arms 16 will move with the arms 60 when the latter are oscillated by the crank arms 68. This latter connection comprises, in each case, a link 72 (Figs. 2 and 3) pivoted at 30 74 to the arm 60 and at 76 to a block 78 slidable in a groove 80 in a bracket 82 rigidly connected to the swing arm 16. It is clear then that the swing arms 16 will oscillate with the arms 60 (of the gage member 42) when the latter are 35 oscillated by the crank arms 68 since the swing arms 16 are connected at two places (by rod 70 or 71 and by link 72) on opposite sides of the shaft 18. To permit the described adjustment of the arms 16 on the arms 60, the arm 16 at the 40 right in Fig. 1 has a slotted portion 83 at its axis of rotation to clear the shaft 18.

45 The reason for connecting the link 72 to the swing arm 16 by means of a sliding block 78 resides in the fact that the gage member 40 is by 45 this means enabled to adjust the position of the swing arms 16 and, perforce, of the bed roll 12 as a result of the caliperizing operation. Since the arms 60 supporting the gage member 42 are connected to the bed roll swing arms 16 at two points, as just mentioned, said gage member 42 is the 50 relatively stationary gage member at the time of caliperizing the work. A piece of work introduced between the gage members 40 and 42 will cause relative movement between the gage members, the gage member 40 moving to the left in Fig. 2, such movement of the gage member 40 causing rotation of the shaft 18 in a counterclockwise direction with the result that an arm 34 (Fig. 3) secured to the shaft 18 is also moved in a counterclockwise direction and thus pulls downwardly upon the adjacent end of the lever 72 through a link connection 86 extending between the arm and the lever. Downward movement of this end of the lever 72 results in upward movement in the other end of said lever 72 whereby the block 78 is moved along the groove 80 in the bracket 82, this movement of the block having the result of adjusting the upper ends of the swing arms 16 a certain distance to the 55 right in Figs. 2 and 3, that is, in a direction away from the corresponding ends of the arms 60. It follows, therefore, that movement of the gage member 40 to the left in Fig. 2 away from the gage member 42 results in adjusting the upper 60 65 70 75 80 85 90 95 100 105 110 115 120 125 130 135 140 ends of the swing arms 16 to the right in Figs. 2 and 3 away from the adjacent upper ends of the arms 60. Since the arms 60 which carry the gage member 42 rock about the shaft 18 and are moved to swing through predetermined arcs through link connections with the crank arms 68, it follows that adjustment of the swing arms 16 with respect to the arms 60 effects also adjustment of the bed roll 12 with respect to the 10 bladed cylinder 10. This adjustment of the swing arms 16 with respect to the arms 60 has just taken place in the position of the parts shown in Figs. 2 and 3 of the drawings. As the bed roll 12 and gage members 40, 42 move further toward the bladed cylinder 10, means is operated to lock the swing arms 16 in their adjusted positions with respect to the arms 60 so that the gaged position of the bed roll will be maintained while the machine is operating upon 20 the piece of work which has just been gaged or calipered.

The locking means referred to above comprises ratchet wheels or plates 90, 92 (Figs. 1 and 3) rotatably mounted on the rod 71 carried by the 25 lower ends of the swing arms 16 and 60 at the right end of the machine in Fig. 1, the said rod 71 serving also as a shaft as will hereinafter be described. As shown, there are provided spring 30 pressed pawls 96, 98 arranged to engage respectively with the ratchet wheels or plates 90 and 92, the teeth of which face in opposite directions so that pawl 96 prevents rotation of the ratchet wheels in a counterclockwise direction in Fig. 3 while pawl 98 prevents rotation in a clockwise direction in the same figure, it being understood that the ratchet wheels 90, 92 with a hub portion thereof extending to the right of the wheels in Fig. 1 are all joined together to move as one piece. As shown, the pawls 96 and 98 35 are pivotally carried by a rod 100 rigidly mounted on an adjacent portion of the swing arm 16. Secured at 102 to the hub of the ratchet wheels 90, 92 is a metallic band 104 which is passed helically around the hub and also around a pulley 40 106 secured to the shaft 18, said metallic band being also secured to the pulley 106 at the point 108. It follows that when the ratchet wheels 90, 92 are locked against rotation in either direction, the shaft 18 is also locked against rotation in either direction. Hence after shaft 18 has been adjusted by the 45 caliper or gaging means 40, 42, as above described, it is locked in its adjusted position by locking means including the pawls 96, 98.

For releasing the locking means, that is, for moving the pawls 96, 98 to unlocking position so that adjustment of the bed roll 12 with respect to the bladed cylinder 10 may be made upon introduction of each fresh piece of work, there is provided in the illustrated construction a control mechanism for the locking means comprising disk 110 (Figs. 1 and 2) carrying four equally spaced pins 112, each of which is provided with an antifriction roll to lessen friction as the pin sweeps along a portion of the upper edge of a lever 114 pivoted at 116 on the machine frame, the said lever 114 being held by a spring 118 with an end portion thereof projecting into the path of pins 112. At each revolution of the cranks 68 on the power shaft 30, the lower ends of the swing arms 16 and 60 are swung alternately to the right and to the left in Fig. 2, this figure illustrating the bed roll 12 as approaching its work presenting position with respect to the cylinder 10, so that the lower ends of the swing

arms 16 and 60 are approaching the end of their swing to the right in Fig. 2, during which movement the disk 110 is being rotated in the direction of the arrow through the engagement of one of the pins 112 with the free end of the lever 114. Rotation of the disk 110 is accompanied by rotation of the rod 71 (serving as a shaft) to which the disk is fastened. Also fastened to the shaft 71 is a cam disk 120 having two sets of cams, one set comprising cams 122, 124 being very clearly shown in Fig. 4 of the drawings, there being a corresponding pair of cams 126, 128 diametrically opposite cams 122, 124. As most clearly shown in Figs. 3 and 4, the cams 122 and 124 have caused lifting of the pawls 96 and 98 the said pawls being provided with cam-ended pins 130, 132, respectively, which ride upon the cams to lift the pawls to inoperative position. Subsequently during continued rotation of the cam disk 120, the pins 130, 132 drop off the cams 20 to permit re-engagement of the pawls 96 and 98 with ratchet wheels 90 and 92, respectively. As already pointed out there are but two sets of cams on the cam disk 120, the sets being diametrically opposite each other. Consequently the 25 ratchet wheels 90, 92 are unlocked and again relocked only twice in a complete revolution of the shaft 71 and of the disk 110. This means that the bed roll 12 is locked in its adjusted position with respect to the gage member 42 and with respect to the bladed cylinder 10 following a caliper 30 operation and for the succeeding cycle of the machine also, the purpose being to maintain the adjusted position of the bed roll while a given piece of work is being operated upon twice to complete treatment thereof, it being understood that each piece of work is introduced twice into the machine since approximately one-half of the work is treated in any given cycle of the machine.

Occasionally it may happen that the operator 35 desires to reintroduce a piece of work without changing the adjusted position of the bed roll as effected by calibration of the same or a previous piece of work. In that case he may depress a treadle 140 (Fig. 1) pivoted at 142 on the frame 40 of the machine and connected by a chain 144 to the lever 114 so that the latter may be depressed to remove its operative end from the path of the pins 112 on the disk 110. Then the disk 110, shaft 71, and cam disk 120 will not be 45 rotated to effect release and resetting of the pawls 96, 98. As shown in Fig. 1, the auxiliary treadle 140 is positioned above a clutch treadle 150 so that it may be readily depressed by the same 50 foot that operates the clutch treadle to control operations of the machine.

As a matter of precaution there is provided a stop member 146 held yieldingly by a spring 148 in the path of the pins 112 on the disk 110 to prevent an idle reverse movement of the disk 110.

To facilitate sorting of the hides as they come from the fleshing machine there is provided an indicator comprising means for visually indicating the thickness dimension of each side undergoing the fleshing operation so that the operator 65 may sort the hides in selected piles according to the indicated thickness dimension. As illustrated, the indicating means comprises a dial 160 (Fig. 1) over which travels a pointer 162 carried by a spindle provided with a drum 164 with which is engaged a chain 166 held in engagement with the drum by a weight 168, the other end of the chain being arranged to pass over an idler wheel 170 mounted upon a stationary extension of the machine frame, the chain being secured to a 70 75

metal band or ribbon 172 (Fig. 3) in turn connected to a metallic band or ribbon 174 arranged to be wound upon a wheel 176 having a grooved periphery to receive the band 174. The wheel 176 is secured to a shaft 178 mounted in a bracket 179 secured to the machine frame, the shaft 178 being provided with a hub upon which winds a tape 180, the other end of which is secured to the free end of a lever 182 pivotally mounted on a shaft 184, the arrangement being such that the lever 182 is operated by a link connection 186 with a lever 188 arranged to be operated by the lever 72 of the bed roll adjusting means. The lever 72 is not directly connected to the lever 188 but is so connected as to make lever 188 responsive to the different adjusted positions of the lever 72. For this purpose the lever 188 has a notched end portion 190 (Figs. 3 and 5) adapted to be contacted by a knife edged member 192 carried by the end of the lever 72. Upon inspection of the drawings, it will be clear that the greater the movement of the upper end of the swing arm 16 to the right away from the gage carrying arm 60 (that is, the greater the distance 25 of the bed roll 20 from the cylinder 10) the greater will be the depression of the knife-member carrying end of the lever 72. With maximum depression of the knife-member carrying end of the lever 72 the knife member 192 will contact with the flat end 194 of the lever 188, with the result that the lever 188 will be operated to maximum extent, in which case the pointer 162 moving over the dial 160 will indicate a hide of the maximum thickness for which the machine is set. On the other hand, lighter hides will not depress the knife-member carrying end of the lever 72 to such an extent as that above mentioned, in which case the knife-member 192 will engage with a slanting surface 196 on the end of the lever 188, thus providing for a much less downward movement of the lever 188, with the result that the pointer will indicate a hide of lesser thickness. In this connection it is to be remembered that, in Figs. 2 and 3, the bed roll 12 and the swing arms 16 and 60 have not completed their movement to the left into work presenting position with respect to the bladed cylinder 10 and it is during this movement that the lever 188 is depressed by the lever 72. Subsequently the lever 72 is locked in its recently adjusted position through locking of the shaft 18. Hence the pointer 162 is held in indicating position, in accordance with the caliper of the hide by the caliper or gaging members 40, 42, during all the time that the bed roll 12 is pressing the work against the cylinder 10. Therefore the indicator may easily be read during that time. When the swing arm 16 moves away from set screw 193 (Fig. 3) carried by a bell crank lever 195, a brake lever 197 connected to bell crank lever 195 by a link 199 is permitted to engage the periphery of a brake wheel 203 to brake the latter, thereby preventing the indicating pointer 162 and connected parts from swinging back to zero position with all the jar and wear and tear involved. The brake does not hold the indicator parts in indicating position but only prevents unnecessary noise and wear on the parts.

When the bed roll 12 is swung to open position, in which a piece of work may be thrown over the bed roll as a preliminary to treatment thereof, means becomes operative to swing the gage member 40 away from the gage member 42 so that a depending portion of a piece of work will readily drop in between the two gage

members when the piece of work is thrown over the bed roll 12. This means comprises, as before described, the stops 50 mounted on the machine frame in position to engage the arms 46 of the bell crank levers 44 whereby the bell 5 crank levers 44 are held from following the swing arms 16 and 60, the bed roll 12 being at the upper end of the swing arms 16. Hence the gage member 40 is left behind while the gage member 42 moves with the bed roll 12 as the 10 latter swings to work receiving position. It will be readily understood that the gage members approach each other and finally caliper the work as the bed roll swings in the opposite direction to present the work to the cylinder 10. 15 It is also desirable that the gage member 40 should move away from the gage member 42 after the caliper operation and after locking of the bed-roll swing arms 16 in adjusted position with respect to the gage swing arms 20 60. The purpose of this separation of the gage members 40, 42 is to release the work so that it is not dragged between these two gage members while being operated upon and fed out of the machine. The means for causing this separation of the gage members 40, 42 comprises a lever 200 (Fig. 1) mounted pivotally upon the rod 70, and an exactly similar lever 201 (Figs. 1 and 2) mounted on shaft 71, and having its upper arm in sliding engagement with an arm 30 202 projecting downwardly from the bell crank lever 44. As the lower ends of the swing arms 16 and 60 continue their movement to the right in Fig. 2, a set screw 204 adjustably carried in the lower arm 206 of the lever 201 (the same being true of lever 200) engages with the machine frame, thereby causing rotation of the lever 201 and 200) in a clockwise direction about the shaft 71 and rod 70, the levers 200 and 201 being in this way caused to operate the bell 40 crank levers 44 in a counterclockwise direction (Fig. 2) to move the gage member 40 away from the gage member 42.

In operating the machine shown in the drawings, a hide is placed upon the bed roll 12 when the latter is in open or work receiving position, a depending portion of the hide dropping in between the gage members 40, 42 which at the time are spaced rather widely from each other. Upon depressing the treadle 150, the clutch (not shown) is thrown in with the result that the bed roll 12 is moved toward the bladed cylinder 10 until it presses the work thereagainst. When the bed roll reaches the position shown in Fig. 2 a gaging or caliper operation is performed by the gage members 40 and 42 accompanied by adjustment of the bed roll swing arms 16 relative to the gage supporting swing arms 60 by which the bed roll 12 is adjusted with respect to the bladed cylinder 10 in accordance with 60 the thickness of the work to be operated upon. Almost immediately after this adjustment of the bed roll, the pawls 96 and 98 operate to lock the adjusting parts and the bed roll 12 in their adjusted positions so that as the bed roll presents the work to the bladed cylinder 10 and to the feed roll 20, the bed roll maintains its proper spaced relation with respect to these members during treatment of that piece of work. During treatment by the cylinder 10 the work 70 is being fed out of the machine in a direction toward the operator, approximately one-half of the piece of work being operated upon at each introduction of the work into the machine. When the work has been completely fed out the 75

operator again depresses the treadle 150 whereupon the bed roll 12 again moves to work receiving position. Then the piece of work is reversed upon the bed roll with the untreated portion depending from the side of the bed roll adjacent to the bladed cylinder. A third depression of the treadle 150 results in movement of the bed roll 12 to work presenting position with respect to the cylinder 10, no effective caliper 10 of the work taking place this time since the pawls remain locked during this second treatment of the same piece of work. After the piece of work has been fed out again, the treadle 150 is depressed for the fourth time in order to bring the work support 12 into work receiving position for a fresh piece of work. Upon receiving the treated piece of work, the operator places it in a pile with other pieces of the same thickness dimension as indicated by the pointer 20 162 and dial 160.

Having described my invention, what I claim as new and desire to secure by Letters Patent of the United States is:

1. In a machine for operating upon hides, skins, and pieces of leather, a bladed cylinder and a bed roll relatively movable with respect to each other to engage and operate upon a piece of work while the latter is backed by the bed roll, yieldingly operated means for causing the described relative movement of the bed roll and cylinder, and means controlled by the work to effect in a positive manner adjustment of the bed roll and cylinder with respect to each other whereby the latter are relatively adjusted automatically for each piece of work introduced into the machine.

2. In a machine for operating upon hides, skins, and pieces of leather, bed roll and cylinder members one of which is movable toward and from the other to permit the introduction of a piece of work, means for moving the movable member, and gaging means carried by the movable member operative automatically to adjust said movable member with respect to the other member in accordance with the thickness of each piece of work.

3. In a machine for operating upon hides, skins, and pieces of leather, bed roll and cylinder members one of which is movable toward and from the other to permit the introduction of a piece of work, means for moving the movable member, and gage members one of which is movable with the said movable member so that a piece of work introduced between the bed roll and cylinder members will also be introduced between the gage members, said gage members being operable to gage the work during relative approaching movement of the bed roll and cylinder members, and having connections with said movable member to adjust the normal spacing between said bed roll and cylinder members when in work treating position.

4. In a machine for operating upon hides, skins, and pieces of leather, bed roll and cylinder members one of which is movable toward and from the other to permit the introduction of a piece of work, means for moving the movable member, gaging means carried by the movable member operative automatically to adjust said movable member with respect to the other member in accordance with the thickness of each piece of work, said adjustment taking place preliminarily to a work treating operation, and means under the control of the operator to secure maintenance of

the adjusted position of the two members during repeated operations of the machine.

5. In a machine for operating upon hides, skins, and pieces of leather, bed roll and cylinder members one of which is movable toward and from the other to permit the introduction of a piece of work, means for moving the movable member, gaging means carried by the movable member operative automatically to adjust said movable member with respect to the other member in accordance with the thickness of each piece of work, and means responsive to the gaging means to indicate to the operator the thickness dimension of each piece of work following gaging thereof.

6. In a machine for operating upon hides, skins, and pieces of leather, bed roll and cylinder members one of which is movable toward and from the other to permit the introduction of a piece of work, means for moving the movable member, gaging means carried by the movable member operative automatically to adjust said movable member with respect to the other member in accordance with the thickness of each piece of work, and indicating means including a dial and a pointer responsive to the gaging means for indicating thickness dimensions of each piece of work introduced into the machine.

7. In a machine for operating upon hides, skins, and pieces of leather, a bladed cylinder, a bed roll movable between work receiving position and work presenting position with respect to said bed roll, and work gaging means controlled by the work and automatically operative to adjust the normal spacing of the bed roll with respect to the bladed cylinder for each piece of work introduced into the machine.

8. In a machine for operating upon hides, skins, and pieces of leather, a bladed cylinder, a bed roll movable between work receiving and work presenting position with respect to said bed roll, work gaging members one of which is movable with the bed roll so that as the bed roll moves to work receiving position the gage members become spaced to permit the introduction of work for a gaging operation, and connections between the work gaging members and the bed roll to adjust the normal spacing of the latter with respect to the bladed cylinder for each piece of work calipered by the work gaging members.

9. In a machine for operating upon hides, skins, and pieces of leather, a bladed cylinder, a bed roll movable between work receiving position and work presenting position with respect to said cylinder, work gaging means automatically operative to adjust the normal spacing of the bed roll with respect to the bladed cylinder for each piece of work introduced into the machine, and means for locking the bed roll in its adjusted position with respect to the bladed cylinder.

10. In a machine for operating upon hides, skins and pieces of leather, a bladed cylinder, a bed roll movable between work receiving position and work presenting position with respect to said bed roll, work gaging means automatically operative to adjust the normal spacing of the bed roll with respect to the bladed cylinder for each piece of work introduced into the machine, said gaging means operating to gage the work as the bed roll moves toward the bladed cylinder, means for locking the bed roll in its adjusted position with respect to the bladed cylinder, and means under the control of the operator for preventing release of the locking means during repeated operation of the machine.

11. In a machine for operating upon hides,

skins, and pieces of leather, a bladed cylinder, a bed roll movable between work receiving and work presenting positions with respect to the bladed cylinder, means for causing such movements of the bed roll, a gage member movable with the bed roll in its described movements toward and from the bladed cylinder, a second gage member, and connections between the first-mentioned gage member and the bed roll to adjust the latter relatively to the bladed cylinder.

12. In a machine for operating upon hides, skins, and pieces of leather, a bladed cylinder, a bed roll movable between work receiving and work presenting positions with respect to the bladed cylinder, means for causing such movements of the bed roll, a gage member movable with the bed roll in its described movements toward and from the bladed cylinder, a second gage member, connections between the first-mentioned gage member and the bed roll to adjust the latter relatively to its moving means and thus to the bladed cylinder, and means for locking the bed roll in adjusted relation to its moving means whereby the spacing of the bed roll with respect to the bladed cylinder is maintained during treatment of a given piece of work.

13. In a machine for operating upon hides, skins, and pieces of leather, a bladed cylinder, a bed roll movable between work receiving and work presenting positions with respect to the bladed cylinder, swing arms for supporting the bed roll, a shaft upon which said swing arms are mounted, a gage member connected to said swing arms and also pivotally mounted on said shaft, a second gage member arranged to adjust the bed roll and the first-mentioned gage member relatively to each other, and power means connected to the first-mentioned gage member to operate the bed roll between work receiving and work presenting positions.

14. In a machine for operating upon hides, skins, and pieces of leather, a tool for operating on a piece of work, a work support movable between work receiving and work presenting positions with respect to said tool, a gage member movable with the work support, a second gage member arranged to be held against movement with the work support, the gage members becoming operative to gage the work as the work support moves toward work presenting position with respect to said tool, and connections between the gage members and the work support to adjust the latter in its normal spacing with respect to said tool.

15. In a machine for operating upon hides, skins, and pieces of leather, a tool for operating on a piece of work, a work support movable between work receiving and work presenting positions with respect to said tool, a gage member having a normally fixed spacing with respect to said tool when the work support is in said work presenting position, a second gage member arranged to become operative in connection with the first-mentioned gage member as the work support moves to work presenting position with respect to said tool, a connection between the first-mentioned gage member and the work support, and means operated by the second-mentioned gage member to adjust the said connection whereby the work support is adjusted in its normal spacing with respect to said tool.

16. In a machine for operating upon hides, skins, and pieces of leather, a tool for operating on a piece of work, a work support movable between work receiving and work presenting posi-

tions with respect to said tool, a gage member movable with the work support and having a normally fixed spacing with respect to said tool when the work support is in said work presenting position, a second gage member pivotally mounted with respect to said work support and arranged to become operative in connection with the first-mentioned gage member to gage the work as the work support moves to work presenting position with respect to said tool, a pivotal connection between the first-mentioned gage member and the work support, and means operated by the second-mentioned gage member to adjust said pivotal connection whereby the work support is adjusted with respect to said tool.

17. In a machine for operating upon hides, skins, and pieces of leather, a tool for operating on a piece of work, a work support movable between work receiving and work presenting positions with respect to said tool, a gage member movable with the work support, a second gage member pivotally mounted on the work support, connections between the gage members and the work support to adjust the latter with respect to said tool, and means operated in timed relation to the movements of the work support to lock the work support in its adjusted relation to said tool.

18. In a machine for operating upon hides, skins, and pieces of leather, a tool for operating on a piece of work, a work support movable between work receiving and work presenting positions with respect to said tool, a gage member movable with the work support, a second gage member pivotally mounted on the work support, connections between the gage members and the work support to adjust the latter with respect to said tool, and a pawl and ratchet mechanism arranged to lock the work support in its adjusted relation to said tool.

19. In a machine for operating upon hides, skins, and pieces of leather, a bladed cylinder, a bed roll movable between work receiving and work presenting positions with respect to said cylinder, a gage member mounted to move with the bed roll, a second gage member mounted to move toward and from the first-mentioned gage member, an adjustable connection between the first-mentioned gage member and the bed roll arranged to be operated by the second-mentioned gage member to adjust the bed roll to the cylinder, means for locking the bed roll in its adjusted position, and means operated in timed relation to the recited movements of the bed roll to render said locking means alternately operative and inoperative.

20. In a machine for operating upon hides, skins, and pieces of leather, a tool for operating on a piece of work, a work support movable between work receiving and work presenting positions with respect to said tool, a gage member movable with the work support, a second gage member pivotally mounted on the work support, connections between the gage members and the work support to adjust the latter with respect to said tool, a pawl and ratchet mechanism arranged to lock the work support in its adjusted relation to said tool, and a cam wheel operated in timed relation to the movements of the work support to cause locking and unlocking of the ratchet wheel by said pawl.

21. In a machine for operating upon hides, skins, and pieces of leather, a bladed cylinder, a bed roll movable between work receiving and work presenting positions with respect to said

cylinder, a gage member mounted to move with the bed roll, a second gage member mounted to move toward and from the first-mentioned gage member, an adjustable connection between the 5 first-mentioned gage member and the bed roll arranged to be operated by the second-mentioned gage member to adjust the bed roll to the cylinder, means for locking the bed roll in its adjusted position, and a pin-wheel movable with 10 the bed roll and arranged to be operated in timed relation to the swinging movements of the bed roll and arranged to operate the locking means to render the latter alternately operative and inoperative.

15 22. In a machine for operating upon hides, skins, and pieces of leather, a bladed cylinder, a bed roll, swing arms for supporting the bed roll and moving the latter between work receiving and work presenting positions with respect to the 20 bladed cylinder, a shaft for supporting said swing arms, a gage member secured to and movable with said bed roll, a connection between said gage member and the bed roll adjustable to vary the 25 positions of the gage member and bed roll relative to each other, a second gage member mounted on said shaft and operative to adjust said connection, means for locking the bed roll and first-mentioned gage member in adjusted position, means connected to said first-mentioned gage 30 member to cause swinging of the bed roll toward and from said cylinder, means to lock the first-mentioned gage member and the bed roll in adjusted position with respect to each other, and means carried by the swing arms to operate the 35 locking means to render the latter alternately operative and inoperative.

23. In a machine for operating upon hides, skins, and pieces of leather, a bladed cylinder, a bed roll, swing arms for supporting the bed 40 roll and moving the latter between work receiving and work presenting positions with respect to the bladed cylinder, a shaft for supporting said swing arms, a gage member secured to and movable with said bed roll, a connection between said 45 gage member and the bed roll adjustable to vary the positions of the gage member and bed roll relative to each other, a second gage member mounted on said shaft and operative to adjust said connection, means for locking the bed roll and first-mentioned gage member in adjusted position, means connected to said first-mentioned 50 gage member to cause swinging of the bed roll toward and from said cylinder, means to lock the first-mentioned gage member and the bed roll in adjusted position with respect to each other, and a pin-wheel carried by one of the swing arms and arranged to be operated in timed relation 55 to the swinging movements of the bed roll to effect alternately locking and unlocking of said locking means.

24. In a machine for operating upon hides, skins, and pieces of leather, a bladed cylinder, a bed roll movable between work receiving and work presenting positions with respect to said cylinder, swing arms for supporting and moving the bed roll, a shaft upon which the swing arms are mounted, a gage member pivotally mounted upon said shaft, a connection between said gage member and the swing arms of the bed roll, a second gage member arranged to adjust said connections in accordance with the thickness of the work between said gage members, means connected to the first-mentioned gage member for causing swinging movements of said bed roll swing arms, means to lock the bed roll and the first-mentioned gage member in their adjusted positions, and a pin-wheel arranged to be operated during the swinging movements of the swing arms to effect alternate locking and unlocking of the bed roll with respect to said first-mentioned gage 15 member.

25. In a machine for operating upon hides, skins, and pieces of leather, a tool for operating on a piece of work, a work support movable between work receiving and work presenting positions with respect to said tool, a gage member movable with the work support, a second gage member arranged to be held against movement with the work support, the gage members becoming operative to gage the work as the work support moves toward work presenting position with 25 respect to said tool, connections between the gage members and the work support to adjust the latter with respect to said tool, and indicating means arranged to be operated by said connections while in their adjusted position, whereby the result of the gaging operation is indicated to the operator.

26. In a machine for operating upon hides, skins, and pieces of leather, a tool for operating on a piece of work, a work support movable between work receiving and work presenting positions with respect to said tool, a gage member movable with the work support, a second gage member arranged to become operative in connection with the first-mentioned gage member as the work support moves to work presenting position with respect to said tool, a connection between the first-mentioned gage member and the work support, means operated by the second-mentioned gage member to adjust the said connection whereby the work support is adjusted with respect to said tool, indicating means, and a member connected to the indicating means and arranged to be operated by said connection as the work support approaches work presenting position with respect to said tool, whereby the indicating means is rendered responsive to the gaging operation.

HARRIE A. BALLARD. 60
